PUFFED TEXTILE FABRIC

Clement R. Howell, Winnsboro, S.C., assignor to United States Rubber Company, New York, N.Y., a corporation of New Jersey

Application December 11, 1957, Serial No. 48,865

Term of patent 14 years

(Cl. D92—1)

Fig. 1

Fig. 2

Fig. 1 is a plan view of a puffed textile fabric showing my new design, and

Fig. 2 is a sectional view of the fabric of Fig. 1 along line 2—2.

The design is embodied in a puffed textile fabric having a surface provided with puffs appearing on the wave like ridges in Fig. 1. In the embodiment shown, the puffs are held raised by threads interlaced in the fabric such as represented by the straight line of Fig. 2.

I claim:

The ornamental design for a puffed textile fabric, as shown and described.
